<img alt="Figure 2: A detailed cross-sectional view of a material working mechanism. The diagram shows a complex assembly of various mechanical parts, including a main frame (14), a conveyor belt (28), and numerous numbered components (e.g., 69, 104, 105, 106, 107, 108, 109, 110, 111, 112, 113, 114, 115, 116, 117, 118, 119, 120, 121, 122, 123, 124, 125, 126, 127, 128, 129, 130, 131, 132, 133, 134, 135, 136, 137, 138, 139, 140, 141, 142, 143, 144, 145, 146, 147, 148, 149, 150, 151, 152, 153, 154, 155, 156, 157, 158, 159, 160, 161, 162, 163, 164, 165, 166, 167, 168, 169, 170, 171, 172, 173, 174, 175, 176, 177, 178, 179, 180, 181, 182, 183, 184, 185, 186, 187, 188, 189, 190, 191, 192, 193, 194, 195, 196, 197, 198, 199, 200, 201, 202, 203, 204, 205, 206, 207, 208, 209, 210, 211, 212, 213, 214, 215, 216, 217, 218, 219, 220, 221, 222, 223, 224, 225, 226, 227, 228, 229, 230, 231, 232, 233, 234, 235, 236, 237, 238, 239, 240, 241, 242, 243, 244, 245, 246, 247, 248, 249, 250, 251, 252, 253, 254, 255, 256, 257, 258, 259, 260, 261, 262, 263, 264, 265, 266, 267, 268, 269, 270, 271, 272, 273, 274, 275, 276, 277, 278, 279, 280, 281, 282, 283, 284, 285, 286, 287, 288, 289, 290, 291, 292, 293, 294, 295, 296, 297, 298, 299, 300, 301, 302, 303, 304, 305, 306, 307, 308, 309, 310, 311, 312, 313, 314, 315, 316, 317, 318, 319, 320, 321, 322, 323, 324, 325, 326, 327, 328, 329, 330, 331, 332, 333, 334, 335, 336, 337, 338, 339, 340, 341, 342, 343, 344, 345, 346, 347, 348, 349, 350, 351, 352, 353, 354, 355, 356, 357, 358, 359, 360, 361, 362, 363, 364, 365, 366, 367, 368, 369, 370, 371, 372, 373, 374, 375, 376, 377, 378, 379, 380, 381, 382, 383, 384, 385, 386, 387, 388, 389, 390, 391, 392, 393, 394, 395, 396, 397, 398, 399, 400, 401, 402, 403, 404, 405, 406, 407, 408, 409, 410, 411, 412, 413, 414, 415, 416, 417, 418, 419, 420, 421, 422, 423, 424, 425, 426, 427, 428, 429, 430, 431, 432, 433, 434, 435, 436, 437, 438, 439, 440, 441, 442, 443, 444, 445, 446, 447, 448, 449, 450, 451, 452, 453, 454, 455, 456, 457, 458, 459, 460, 461, 462, 463, 464, 465, 466, 467, 468, 469, 470, 471, 472, 473, 474, 475, 476, 477, 478, 479, 480, 481, 482, 483, 484, 485, 486, 487, 488, 489, 490, 491, 492, 493, 494, 495, 496, 497, 498, 499, 500, 501, 502, 503, 504, 505, 506, 507, 508, 509, 510, 511, 512, 513, 514, 515, 516, 517, 518, 519, 520, 521, 522, 523, 524, 525, 526, 527, 528, 529, 530, 531, 532, 533, 534, 535, 536, 537, 538, 539, 540, 541, 542, 543, 544, 545, 546, 547, 548, 549, 550, 551, 552, 553, 554, 555, 556, 557, 558, 559, 560, 561, 562, 563, 564, 565, 566, 567, 568, 569, 570, 571, 572, 573, 574, 575, 576, 577, 578, 579, 580, 581, 582, 583, 584, 585, 586, 587, 588, 589, 590, 591, 592, 593, 594, 595, 596, 597, 598, 599, 600, 601, 602, 603, 604, 605, 606, 607, 608, 609, 610, 611, 612, 613, 614, 615, 616, 617, 618, 619, 620, 621, 622, 623, 624, 625, 626, 627, 628, 629, 630, 631, 632, 633, 634, 635, 636, 637, 638, 639, 640, 641, 642, 643, 644, 645, 646, 647, 648, 649, 650, 651, 652, 653, 654, 655, 656, 657, 658, 659, 660, 661, 662, 663, 664, 665, 666, 667, 668, 669, 669, 670, 671, 672, 673, 674, 675, 676, 677, 678, 679, 680, 681, 682, 683, 684, 685, 686, 687, 688, 689, 689, 690, 691, 692, 693, 694, 695, 696, 697, 698, 699, 699, 700, 701, 702, 703, 704, 705, 706, 707, 708, 709, 709, 710, 711, 712, 713, 714, 715, 716, 717, 717, 718, 719, 719, 720, 721, 722, 723, 724, 725, 726, 727, 728, 729, 729, 730, 731, 732, 733, 734, 735, 736, 737, 738, 739, 739, 740, 741, 742, 743, 744, 745, 746, 747, 748, 749, 749, 750, 751, 752, 753, 754, 755, 756, 757, 758, 759, 759, 760, 761, 762, 763, 764, 765, 766, 767, 768, 769, 769, 770, 771, 772, 773, 774, 775, 776, 777, 778, 779, 779, 780, 781, 782, 783, 784, 785, 786, 787, 787, 788, 789, 789, 790, 791, 792, 793, 794, 795, 796, 797, 798, 799, 799, 800, 801, 802, 803, 804, 805, 806, 807, 808, 809, 809, 810, 811, 812, 813, 814, 815, 816, 817, 818, 819, 819, 820, 821, 822, 823, 824, 825, 826, 827, 828, 829, 829, 830, 831, 832, 833, 834, 835, 836, 837, 838, 839, 839, 840, 841, 842, 843, 844, 845, 846, 847, 848, 849, 849, 850, 851, 852, 853, 854, 855, 856, 857, 858, 859, 859, 860, 861, 862, 863, 864, 865, 866, 867, 868, 869, 869, 870, 871, 872, 873, 874, 875, 876, 877, 878, 879, 879, 880, 881, 882, 883, 884, 885, 886, 887, 888, 889, 889, 890, 891, 892, 893, 894, 895, 896, 897, 898, 899, 899, 900, 901, 902, 903, 904, 905, 906, 907, 908, 909, 909, 910, 911, 912, 913, 914, 915, 916, 917, 918, 919, 919, 920, 921, 922, 923, 924, 925, 926, 927, 928, 929, 929, 930, 931, 932, 933, 934, 935, 936, 937, 938, 939, 939, 940, 941, 942, 943, 944, 945, 946, 947, 948, 949, 949, 950, 951, 952, 953, 954, 955, 956, 957, 958, 959, 959, 960, 961, 962, 963, 964, 965, 966, 967, 968, 969, 969, 970, 971, 972, 973, 974, 975, 976, 977, 978, 979, 979, 980, 981, 982, 983, 984, 985, 986, 987, 988, 989, 989, 990, 991, 992, 993, 994, 995, 996, 997, 998, 999, 999, 1000, 1001, 1002, 1003, 1004, 1005, 1006, 1007, 1008, 1009, 1009, 1010, 1011, 1012, 1013, 1014, 1015, 1016, 1017, 1018, 1019, 1019, 1020, 1021, 1022, 1023, 1024, 1025, 1026, 1027, 1028, 1029, 1029, 1030, 1031, 1032, 1033, 1034, 1035, 1036, 1037, 1038, 1039, 1039, 1040, 1041, 1042, 1043, 1044, 1045, 1046, 1047, 1048, 1049, 1049, 1050, 1051, 1052, 1053, 1054, 1055, 1056, 1057, 1058, 1059, 1059, 1060, 1061, 1062, 1063, 1064, 1065, 1066, 1067, 1068, 1069, 1069, 1070, 1071, 1072, 1073, 1074, 1075, 1076, 1077, 1078, 1079, 1079, 1080, 1081, 1082, 1083, 1084, 1085, 1086, 1087, 1088, 1089, 1089, 1090, 1091, 1092, 1093, 1094, 1095, 1096, 1097, 1098, 1099, 1099, 1100, 1101, 1102, 1103, 1104, 1105, 1106, 1107, 1108, 1109, 1109, 1110, 1111, 1112, 1113, 1114, 1115, 1116, 1117, 1118, 1119, 1119, 1120, 1121, 1122, 1123, 1124, 1125, 1126, 1127, 1128, 1129, 1129, 1130, 1131, 1132, 1133, 1134, 1135, 1136, 1137, 1138, 1139, 1139, 1140, 1141, 1142, 1143, 1144, 1145, 1146, 1147, 1148, 1149, 1149, 1150, 1151, 1152, 1153, 1154, 1155, 1156, 1157, 1158, 1159, 1159, 1160, 1161, 1162, 1163, 1164, 1165, 1166, 1167, 1168, 1169, 1169, 1170, 1171, 1172, 1173, 1174, 1175, 1176, 1177, 1178, 1179, 1179, 1180, 1181, 1182, 1183, 1184, 1185, 1186, 1187, 1188, 1189, 1189, 1190, 1191, 1192, 1193, 1194, 1195, 1196, 1197, 1197, 1198, 1199, 1199, 1200, 1201, 1202, 1203, 1204, 1205, 1206, 1207, 1208, 1209, 1209, 1210, 1211, 1212, 1213, 1214, 1215, 1216, 1217, 1218, 1219, 1219, 1220, 1221, 1222, 1223, 1224, 1225, 1226, 1227, 1228, 1229, 1229, 1230, 1231, 1232, 1233, 1234, 1235, 1236, 1237, 1238, 1239, 1239, 1240, 1241, 1242, 1243, 1244, 1245, 1246, 1247, 1248, 1249, 1249, 1250, 1251, 1252, 1253, 1254, 1255, 1256, 1257, 1258, 1259, 1259, 1260, 1261, 1262, 1263, 1264, 1265, 1266, 1267, 1268, 1269, 1269, 1270, 1271, 1272, 1273, 1274, 1275, 1276, 1277, 1278, 1279, 1279, 1280, 1281, 1282, 1283, 1284, 1285, 1286, 1287, 1288, 1289, 1289, 1290, 1291, 1292, 1293, 1294, 1295, 1296, 1297, 1297, 1298, 1299, 1299, 1300, 1301, 1302, 1303, 1304, 1305, 1306, 1307, 1308, 1309, 1309, 1310, 1311, 1312, 1313, 1314, 1315, 1316, 1317, 1318, 1319, 1319, 1320, 1321, 1322, 1323, 1324, 1325, 1326, 1327, 1328, 1329, 1329, 1330, 1331, 1332, 1333, 1334, 1335, 1336, 1337, 1338, 1339, 1339, 1340, 1341, 1342, 1343, 1344, 1345, 1346, 1347, 1348, 1349, 1349, 1350, 1351, 1352, 1353, 1354, 1355, 1356, 1357, 1358, 1359, 1359, 1360, 1361, 1362, 1363, 1364, 1365, 1366, 1367, 1368, 1369, 1369, 1370, 1371, 1372, 1373, 1374, 1375, 1376, 1377, 1378, 1379, 1379, 1380, 1381, 1382, 1383, 1384, 1385, 1386, 1387, 1388, 1389, 1389, 1390, 1391, 1392, 1393, 1394, 1395, 1396, 1397, 1397, 1398, 1399, 1399, 1400, 1401, 1402, 1403, 1404, 1405, 1406, 1407, 1408, 1409, 1409, 1410, 1411, 1412, 1413, 1414, 1415, 1416, 1417, 1418, 1418, 1419, 1420, 1421, 1422, 1423, 1424, 1425, 1426, 1427, 1428, 1429, 1429, 1430, 1431, 1432, 1433, 1434, 1435, 1436, 1437, 1438, 1439, 1439, 1440, 1441, 1442, 1443, 1444, 1445, 1446, 1447, 1448, 1449, 1449, 1450, 1451, 1452, 1453, 1454, 1455, 1456, 1457, 1458, 1459, 1459, 1460, 1461, 1462, 1463, 1464, 1465, 1466, 1467, 1468, 1469, 1469, 1470, 1471, 1472, 1473, 1474, 1475, 1476, 1477, 1478, 1479, 1479, 1480, 1481, 1482, 1483, 1484, 1485, 1486, 1487, 1488, 1489, 1489, 1490, 1491, 1492, 1493, 1494, 1495, 1496, 1497, 1497, 1498, 1499, 1499, 1500, 1501, 1502, 1503, 1504, 1505, 1506, 1507, 1508, 1509, 1509, 1510, 1511, 1512, 1513, 1514, 1515, 1516, 1517, 1518, 1518, 1519, 1520, 1521, 1522, 1523, 1524, 1525, 1526, 1527, 1528, 1529, 1529, 1530, 1531, 1532, 1533, 1534, 1535, 1536, 1537, 1538, 1539, 1539, 1540, 1541, 1542, 1543, 1544, 1545, 1546, 1547, 1548, 1549, 1549, 1550, 1551, 1552, 1553, 1554, 1555, 1556, 1557, 1558, 1559, 1559, 1560, 1561, 1562, 1563, 1564, 1565, 1566, 1567, 1568, 1569, 1569, 1570, 1571, 1572, 1573, 1574, 1575, 1576, 1577, 1578, 1579, 1579, 1580, 1581, 1582, 1583, 1584, 1585, 1586, 1587, 1588, 1589, 1589, 1590, 1591, 1592, 1593, 1594, 1595, 1596, 1597, 1597, 1598, 1599, 1599, 1600, 1601, 1602, 1603, 1604, 1605, 1606, 1607, 1608, 1609, 1609, 1610, 1611, 1612, 1613, 1614, 1615, 1616, 1617, 1618, 1618, 1619, 1620, 1621, 1622, 1623, 1624, 1625, 1626, 1627, 1628, 1629, 1629, 1630, 1631, 1632, 1633, 1634, 1635, 1636, 1637, 1638, 1639, 1639, 1640, 1641, 1642, 1643, 1644, 1645, 1646, 1647, 1648, 1649, 1649, 1650, 1651, 1652, 1653, 1654, 1655, 1656, 1657, 1658, 1659, 1659, 1660, 1661, 1662, 1663, 1664, 1665, 1666, 1667, 1668, 1669, 1669, 1670, 1671, 1672, 1673, 1674, 1675, 1676, 1677, 1678, 1679, 1679, 1680, 1681, 1682, 1683, 1684, 1685, 1686, 1687, 1688, 1689, 1689, 1690, 1691, 1692, 1693, 1694, 1695, 1696, 1697, 1697, 1698, 1699, 1699, 1700, 1701, 1702, 1703, 1704, 1705, 1706, 1707, 1708, 1709, 1709, 1710, 1711, 1712, 1713, 1714, 1715, 1716, 1717, 1718, 1718, 1719, 1720, 1721, 1722, 1723, 1724, 1725, 1726, 1727, 1728, 1729, 1729, 1730, 1731, 1732, 1733, 1734, 1735, 1736, 1737, 1738, 1739, 1739, 1740, 1741, 1742, 1743, 1744, 1745, 1746, 1747, 1748, 1749, 1749, 1750, 1751, 1752, 1753, 1754, 1755, 1756, 1757, 1758, 1759, 1759, 1760, 1761, 1762, 1763, 1764, 1765, 1766, 1767, 1768, 1769, 1769, 1770, 1771, 1772, 1773, 1774, 1775, 1776, 1777, 1778, 1779, 1779, 1780, 1781, 1782, 1783, 1784, 1785, 1786, 1787, 1788, 1789, 1789, 1790, 1791, 1792, 1793, 1794, 1795, 1796, 1797, 1797, 1798, 1799, 1799, 1800, 1801, 1802, 1803, 1804, 1805, 1806, 1807, 1808, 1809, 1809, 1810, 1811, 1812, 1813, 1814, 1815, 1816, 1817, 1818, 1818, 1819, 1820, 1821, 1822, 1823, 1824, 1825, 1826, 1827, 1828, 1829, 1829, 1830, 1831, 1832, 1833, 1834, 1835, 1836, 1837, 1838, 1839, 1839, 1840, 1841, 1842, 1843, 1844, 1845, 1846, 1847, 1848, 1849, 1849, 1850, 1851, 1852, 1853, 1854, 1855, 1856, 1857, 1858, 1859, 1859, 1860, 1861, 1862, 1863, 1864, 1865, 1866, 1867, 1868, 1869, 1869, 1870, 1871, 1872, 1873, 1874, 1875, 1876, 1877, 1878, 1879, 1879, 1880, 1881, 1882, 1883, 1884, 1885, 1886, 1887, 1888, 1889, 1889, 1890, 1891, UNITED STATES PATENT OFFICE.

ARTHUR EHRHOLD SCHULZ, OF CHICAGO, ILLINOIS, ASSIGNOR TO WESTERN ELECTRIC COMPANY, INCORPORATED, OF NEW YORK, N. Y., A CORPORATION OF NEW YORK.

MATERIAL-WORKING MECHANISM.

Application filed August 22, 1924. Serial No. 733,494.

This invention relates to material working mechanisms, and more particularly to a combined slitting and rewinding machine for the purpose of slitting a comparatively 5 wide web of material into strips.

An object of the invention is to provide an improved compact material working mechanism of the above mentioned type which is so organized and arranged as to be efficiently 10 attended by the operator.

Another object of the invention is to provide an improved means for supporting, aligning, and driving cooperating work performing members.

In accordance with one feature of the invention there is provided with a mechanism for slitting a metallic web into a plurality of strips, a rewinding mechanism designed to take up each strip at right angles to the direction of delivery from the slitting mechanism and upon a reel independently driven. Also arranged below the rewinding mechanism is a mechanism for automatically taking up and compacting the scrap material as 20 it accumulates.

In accordance with another feature of the invention there is provided two series of slitting members suitably spaced upon sleeves rotatably secured to driving shafts overhanging the supporting frame of the slitting mechanism, the sleeves being adapted to interlock in mounting them upon the shafts so that the cooperating slitting members carried thereon will be correctly aligned and the securing of one sleeve from longitudinal 30 movement upon its shaft retains the other sleeve. The overhanging shafts permit the slitting members to be readily and easily removed therefrom. The shafts are gear driven, one shaft being driven from the other in a manner which permits a comparatively wide range of adjustment between the slitting members as they wear without being limited by the pitch diameter of the driving 40 gears.

It is believed that the invention will be clearly understood from the following description and the accompanying drawings, in which

Fig. 1 is a side elevation of a mechanism

for slitting metallic webs showing the supply reel and the take-up mechanism in operative relation thereto, along with the scrap take-up mechanism;

Fig. 2 is a plan view thereof;

Fig. 3 is a fragmentary end elevation looking at the right hand end of Fig. 1;

Fig. 4 is an enlarged fragmentary view of a portion of Fig. 1 showing the means for brushing and cleaning the strips after leaving the slitting rolls;

Fig. 5 is a plan view thereof;

Fig. 6 is an enlarged end view partly in section of the slitting disks and driving mechanism therefor;

Fig. 7 is a vertical sectional view taken upon the line 7—7 of Fig. 6 looking in the direction indicated by the arrows;

Fig. 8 is a fragmentary end view of a reel upon which the slit strip is wound;

Fig. 9 is a vertical sectional view taken upon the line 9—9 of Fig. 8 looking in the direction indicated by the arrows;

Fig. 10 is an enlarged fragmentary detail side view of the slitting disks;

Fig. 11 is an enlarged fragmentary side elevation of the tape supply reel, partly in section, and

Fig. 12 is a vertical sectional view taken upon the line 12—12 thereof, looking in the direction indicated by the arrows.

As shown in Fig. 1 the mechanism comprises a main frame or table 14 which serves as a stand for supporting a supply reel 15 and a rewinding mechanism 16 comprising 85 a plurality of take-up reels 17 for the slit web. The slitting mechanism is indicated at 18 and the automatic scrap take-up mechanism at 19. The mechanism illustrated is designed to slit a web into nine strips of 90 equal width and rewind them upon separate reels, each of the reels being independently driven, but it will readily be understood that the number and width of the strips to be slit may be varied without departing from 95 the spirit and scope of the invention.

Slitting mechanism.

The slitting mechanism comprises a pair of shafts 20 and 21 suitably journaled in 100

vertical arrangement upon standards 22 and 23 arranged upon the left-hand end of the frame 14 as viewed in Fig. 1. Also journaled upon the standards 22 and 23 directly below the shafts 20 and 21 is a main drive shaft 24 driven through gearing indicated in dotted outline at 25 in Fig. 2, which is driven from a motor indicated at 26. The shaft 24 through a sprocket wheel 27 and a pulley 28 affixed thereto drives the take-up reels 17 and the scrap take-up mechanism 19 respectively through cooperating means which will be referred to hereafter. Secured to the shaft 24 intermediate the standards 22 and 23 is a gear 29 which meshes with a gear 30 secured to the shaft 21, which gear in turn meshes with a comparatively wide faced gear 31 affixed to a shaft 32 rotatably mounted in the same horizontal plane as the shaft 21 upon a depending bracket 33 supported from a horizontally extending bridge portion 36 connecting the standards 22 and 23. Also rotatably mounted upon the bracket 33 and in vertical and horizontal alignment with the shafts 32 and 20 respectively is a shaft 37. Affixed to the shaft 37 and offset with respect to the gear 30, as viewed in Fig. 6, and adapted to mesh with the wide faced gear 31 is a gear 38 in turn meshing with a gear 39 secured to the shaft 20.

The standards 22 and 23 are each provided with an elongated opening 40 within which are slidably mounted journals 43 for supporting the shafts 20 and 21. Suitably mounted between each pair of vertically disposed journals 43 is a compression spring 44, and screw threaded into the top surface of each of the standards 22 and 23 is an adjusting screw 45, the lower ends of which engage the top surface of the journals 43 associated with the shaft 20. By turning the screws 45 down it will readily be seen that the shaft 20 will be moved downward against the compression of the springs 44, and upon turning the screws 45 upward the springs 44 function to move the shaft 20 upward. The purpose of this vertical adjustment of the shaft with respect to the shaft 21 will be made apparent later on in the description. It will thus be evident that upon a rotary motion being applied to the shaft 24 in the direction indicated by the arrow in Fig. 7, that the shaft 21 will be rotated in a clockwise direction through the cooperating gears 29 and 30, the latter gear causing the rotation of the wide faced gear 31, which in turn drives the gear 38 mounted directly thereabove and thereby causes the rotation of the shaft 20 in a counter-clockwise direction through the co-operating gear 39. The shafts 20 and 21 extend outside of the right hand side of the standard 23 and mounted upon each of the shafts is a set of slitting disks 46 and 47 respectively. The overhanging ends of the shafts 20 and 21 are each provided with an integral collar 48

which lies snug against the surface of the journals 43. Secured to the shaft 20 by keys 50, indicated in dotted outline, is a sleeve 51 mounting a plurality of slitting disks 52 and spacing rings 53. The sleeve 51 is provided at its left hand end, as indicated at 54, with a head. Also mounted upon the sleeve 51 is a pair of aligning collars 55 suitably spaced by a spacing ring 53. The slitting disks 52, spacing rings 53, and aligning collars 55 are clamped upon the sleeve 51 and against the head 54 formed thereon by a clamping nut 58 screw threaded upon the sleeve 51. A second clamping nut 59 screw threaded upon the end of the shaft 20 prevents any longitudinal displacement of the assembled sleeve upon the shaft 20 by clamping it against the collar 48. A sleeve 61 similar to the sleeve 51 upon the shaft 20, is similarly keyed to the shaft 21 and also carries a plurality of disks 62 and spacing rings 63. An aligning collar 65 suitably spaced upon the sleeve 61 by the spacing rings 63 cooperates with the spaced aligning collars 55 upon the sleeve 51 to accurately align the disks 62 which have been suitably spaced upon the sleeve 61 by the spacing rings 63 to align with the space between the disks 52 mounted upon the sleeve 51. The disks 62, spacing rings 63, and the aligning collar 65 are clamped upon the sleeve 61 and against a head 64 formed thereon by a clamping nut 68. The disks 52 and 62 being assembled correctly upon the sleeves 51 and 61 respectively, and thereafter the sleeves upon the overhanging ends of the shafts 20 and 21 respectively, provides a means for readily removing or mounting the assembled slitting units upon their respective supports. No accurate adjustment of one set of slitting disks with respect to the other is necessary when mounting them in position upon the shafts 20 and 21, it being merely necessary to align the collar 65 between the collars 55 and slide the sleeves 51 and 61 in position upon the shafts 20 and 21 respectively, thereafter the two slitting units are retained longitudinally upon the shafts 20 and 21 by threading the clamping nut 59 upon the end of the shaft 20.

Due to the mounting and driving arrangement of the slitting disks as heretofore described, a large range of adjustment may be made as they wear without being limited by the pitch diameter of the driving gears. As wear shows on the disks, the screw 45 may be turned down against the action of the spring 44 until the proper slitting relation exists between the slitting edges of the disks 52 and 62.

A supply reel 15, which will be described in greater detail hereafter, is carried upon a bracket 69 supported upon the frame or table 14, and the web 70 to be slit is led therefrom and under a roller 71, riding in a bath of some suitable lubricant, which may be water, indicated at 72, the purpose of which is to wet the

tape, the water thereon being carried to the cutters to supply a lubricant therefor.

From the roller 71 the web 70 is guided between the slitting disks 52 and 62 by suitable upper and lower guiding plates 73 and 74, provided with guiding fingers 76 and 77 respectively (Fig. 10), which prevent the strips 78 from following the periphery of the slitting disks 52 and 62, but guide them to the rewinding mechanism 16.

Scrap material take-up.

The scrap material 79 removed from the outside edges of the web 70 is guided downwardly by fingers 80 (Fig. 10), one provided at each side of the web 70 to the automatic scrap take-up mechanism 19 situated below the rewinding mechanism 17. This mechanism comprises a reel 83 adapted to be rotated counter-clockwise about a shaft 84, carrying at one end a pulley 85 which is driven by the pulley 28 through a belt 86. Suitably hinged to the slitting mechanism 18 is a guide pan or apron 87 comprising a bottom wall 90 and side walls 91, the side walls being spaced just inside the flanges of the reel 83. The lower end of the bottom wall 90 is curved upward within the periphery of the reel 83 and has attached thereto one end of a tension spring 92, the opposite end of the spring being secured to the frame 14. The flanges of the reel 83 are secured together upon the shaft 84 by a plurality of equally spaced pins 93, indicated in Fig. 1. The strips of scrap material 79 are secured to one of the pins 93 by merely wrapping them around the pin, and in the rotation of the reel 83 the scrap material 79 is coiled thereon, with the apron 87 under the action of the spring 92 automatically compacting the scrap upon the reel 83. If the scrap strip should break during the operation of the machine, it will work its way down the apron 87 and become enmeshed with the scrap wound on the reel and be finally wound thereon.

Strip cleaning device.

Intermediate the slitting mechanism 18 and the rewinding mechanism 16, and supported upon the frame 14, is a device 95 for brushing and cleaning the upper and lower surfaces of the strips 78 of any burrs formed thereon during the slitting operation, or of any foreign matter thereon before they are taken up on the reels 17. This cleaning device may comprise a pair of emery wheels 96, or in some cases may comprise milling cutters or a suitable circular brush, depending upon the material to be cleaned or brushed, the width of which is great enough to span all of the strips 78 (Figs. 1, 4, and 5). One of the wheels 96 contacts with the lower surface of the strips and is rotated clockwise, while the other wheel contacts with the upper surface of the strips and is rotated counter-clockwise. The emery wheels are driven by suitable driving con-

nctions, indicated generally by the numeral 97, through a pinion 98 associated with the gearing 25.

Rewinding mechanism.

The rewinding mechanism comprises a plurality of independently driven take-up reels 17 disposed upon the frame 14 in such a manner that the strips 78 are wound thereupon at right angles to their plane of severance from the web 70 by the slitting disks, or to the direction of delivery from the slitting mechanism without deleterious stresses or strains, and with a minimum use of space. The reason for mounting the reels in this manner is that it would not be practical to mount the reels upon a single spindle and drive each reel independently thereon without the use of a great deal of space. By referring to Figs. 1 and 3 it will be observed that the take-up reels 17 are mounted in two rows, with the reels in the upper row spaced intermediate the reels forming the lower row. It will also be apparent that reels could be mounted below the plane of severance of the strip. The reels 17, a detailed description of which will be given hereafter, are each mounted upon the upper end of a rod 100, the lower end of which is clamped in a bracket 101, one for each rod, suitably mounted upon the frame 14. The brackets 101 for supporting the upper row of reels extend to the rear and upward of the brackets, supporting the lower row of reels, and then are curved forwardly just outside of the periphery of the reels 17, as clearly indicated in Fig. 3, thereby providing a suitable clearance or space for mounting and removing the reeled strips from the reels 17, as will be described hereafter.

Suitably journaled upon the frame 14 at the right hand end as viewed in Fig. 2 is a shaft 102, carrying at one end a sprocket wheel 103, which is driven by the sprocket 27 through a chain 104. Secured to the forward end of the shaft 102, as viewed in Fig. 2, is a bevel gear 107 meshing with a bevel gear 108 affixed to a shaft 109 which extends horizontally across the rewinding mechanism and below the lower row of reels 17 (Fig. 3). Suitably spaced upon the shaft 109 are a plurality of pulleys 110, one for each of the reels 17 mounted in the lower row. Connecting each of the pulleys 110 with a pulley 111 affixed to each of the winding arbors 114 supporting the reels 17 is a driving belt 115. Journaled upon the brackets 101 supporting the upper row of reels 17, as indicated at 116, and positioned above and to the rear of the shaft 109, is a shaft 117 which is operatively connected to the shaft 109 through a chain 118, and cooperating sprocket wheels 119 and 120 affixed to the shafts 109 and 117 respectively. Affixed to the shaft 117 are a plurality of pulleys 123 which through driving belts 124 turn pulleys 125 secured to the wind-

ing arbors 114 supporting the upper row of reels 17. It will thus be seen that upon rotary motion being applied to the main drive shaft 24 that each of the take-up reels 17 will be independently driven through the associated sprocket wheel 27, chain 104, sprocket wheel 103, bevel gears 107 and 108, shafts 109 and 117 operatively connected together by the sprocket wheels 119 and 120, and chain 118, the rotary motion of the shafts 109 and 117 being transmitted to the reels 17 in the lower row through the pulleys 110, 111, belts 115, and to the reels 17 in the upper row by the pulleys 123, 125, and belts 124. By driving each take-up reel 17 through a belt independently of the others, a uniform tension is maintained upon the strips 78, which is desirable in the rewinding of certain materials.

Adjustably supported for vertical movement upon the front face of each of the brackets 101 is a pulley 126 for guiding the strips 78 after leaving the cleaning device 95 on their way to the reels 17. As will be observed from Figs. 1 and 2, each of the pulleys 126 is positioned in a different vertical and horizontal plane so as to maintain the strips separate and prevent interference or tangling between them. Between the pulleys 126 and the take-up reels 17 the strips receive a 90° twist, which produces no deleterious effects thereon, due to the comparatively long distance between the pulleys 126 and the reels 17.

Take-up reels.

Referring to Figs. 8 and 9, which show details of the take-up reels 17, 129 indicates a bearing head affixed to the upper end of the rod 100, upon which is journaled, by anti-friction bearings 130, the winding arbor 114. Affixed to the rotatable arbor 114 by a key 131 is a shouldered circular head 132. Affixed to a shouldered portion of the head 132 at one side thereof is a thin circular plate 133. Removably mounted upon the opposite side 45 of the head 132 is a second thin circular plate 134, the two plates being separated by a circular flange-like portion 137 formed on the head 132. Rotatably secured to the portion 137 by a key (not shown) is a strip or strand carrier 138 of the type illustrated and described in the patent to F. S. Kochendorfer No. 1,545,906, issued July 14, 1925, to which reference may be had for a more detailed illustration and description.

Secured to the outside flat face of the plate 134 is a pair of spring pressed diametrically opposed latches 139, the latching ends 140 of which are adapted to readily engage in a continuous circular channel 141 formed in a shouldered portion of the head 132. The latches 139 are each secured to the plate 134 for radial movement by a pair of shouldered rivets 144 secured to the plate 134, which ride in slots 145 formed in the latches 139. The outside end of each of the latches 139 is bent

outward at right angles to the main portion, as indicated at 146, to form a handle for manipulating the latch against the action of a spring 147 positioned under tension between a housing 148 affixed to the plate 134 and a face of the handle 146 as clearly indicated in Fig. 9. To remove the loaded strip carrier 138 from the reel 17, the operator inserts his hands between two of the reels 17 and pulls outward upon the handles 146 of the latches 139 against the action of the springs 147, which movement brings the latching ends 140 of the latches 139 out of the channel 141, and then by moving the plate 134 parallel to the axis of the winding arbor 114 it may be moved so that the loaded carrier 138 may be easily removed from the portion 137 of the head 132 and replaced by an empty one. In latching the plate 134 upon the head 132 after mounting an empty carrier 138, the latching ends 140 of the latches 139, which are slightly tapered, engage a continuous tapered surface 149 formed upon the head 132, and upon pressing the plate 134 to the left, as viewed in Fig. 9, the latches 139 will ride up the tapered surface 149 against the action of the springs 147 and then drop into the circular channel 141, whereupon the reel 17 is ready to take up the ribbon 78.

Supply reel.

The supply reel 15 illustrated in detail in Figs. 11 and 12 comprises a thin circular plate or head 152 affixed to a spindle 153 rotatably mounted upon the bracket 69. Associated with the head 152 is a second head 154 in the form of a thin circular plate having a plurality of tapered pins 155 concentrically arranged, which form a hub upon which the web 70 is wound. Secured to the head 154 is a shouldered knob or handle 158. A reduced circular portion 159 of the handle 158 is cut away as indicated at 160 within which is mounted a spring pressed latch 161, which is pivotally mounted upon a pin 162. In its latched position an engaging end 163 of the latch 161 enters a circular channel 164 formed in the spindle 153 under the action of a compression spring 166. To remove the head 154 from the spindle the latch 161 is turned counter-clockwise about the pin 162 by pressing inward upon a knurled knob 167 formed upon the latch 161 and against the action of the spring 166, thereby raising the engaging end 163 of the latch from the circular channel 164 and thereafter the head may be slid from off the spindle 153.

In the manufacture of the web 70 it may be taken up directly during its fabrication upon a reel similar to the reel 17 just described, and at times when the web 70 is being produced at a greater speed than it is being slit into the strips 78 by the slitting mechanism 18, the coil or web 70 may be readily and easily removed from the head 154 and stored

until ready to use by simply turning the tapered pins 155 downward and gently tapping the head 154, whereupon the coil of web 70 will drop off of the tapered pins. The coil 5 of web may be readily mounted upon the head 154 again by pressing it into position around the tapered pins 155 as originally coiled.

The operation of this mechanism is as follows: In the particular embodiment of the invention illustrated, a supply reel 15 containing a coil of web 70 is first mounted upon its spindle 153 and thereafter the free end of the web is threaded under the roller 71 mounted in the water bath 72 and then between the guiding plates 73 and 74. From the guiding plates the web is fed between the slitting disks 46 and 47 where it is slit into the strips 78. The scrap material 79 removed from the 10 edges of the web is led under the fingers 80 and wrapped around one of the pins 93, forming the hub of the reel 83. From the slitting disks the strips 78 are threaded between the emery wheels 96 and thereafter they are each 15 passed around their respective guiding pulley 126, given a twist of 90°, led upward and suitably secured to their respective carrier 138. Upon starting the machine the web 70 is continuously drawn from the supply reel 20 15, slit into a plurality of strips 78, each strip being wound upon a separate reel independently driven to provide a uniform tension upon the strips, which in the case of material of a fragile nature is very essential. 25 As the strips are being wound upon their respective reels or carriers, the scrap removed from the sides of the web during the slitting operation is automatically taken up on the reel 83, the apron 87 under the action of the 30 spring 92 automatically compacting the scrap upon the reel. The wide surfaces of the strips are brushed and cleaned by the emery wheels 96 before being wound upon the reels 17 to remove any burrs that might be formed 35 thereon during the slitting operation, or of any foreign matter thereon which may be necessary on account of the use to which the strips may be put. Also at times due to flaws developed in the web 70 during its fabrication, a break may occur in one or the other of the strips, whereupon the machine is 40 stopped, the break repaired by lapping the ends, sometimes leaving this particular strip a trifle short, but due to the separate drive for each reel or carrier, the tension upon the 45 repaired strip as it continues to be taken up is not increased as it naturally would be if all of the strips were taken up on a single spindle.

60 What is claimed is:

1. In a slitting and rewinding machine, means for slitting a strip of predetermined width from a web, and means for taking up said strip in a plane at right angles to its 65 plane of severance.

2. In a slitting and rewinding machine, means for slitting a web into a plurality of strips of predetermined width, and means for taking up one of said strips independently and in a plane at right angles to its plane of 70 severance.

3. In a slitting and rewinding machine, means for slitting a web into a plurality of strips of predetermined width, and means for taking up each of said strips independently 75 and in a plane at right angles to its plane of delivery from the slitting means.

4. In a slitting and rewinding machine, a web supply, means for slitting the web into a plurality of strips, means for lubricating the moving web, means for taking up one of the strips independently and in a plane at right angles to its plane of delivery from the slitting means, and means positioned between 80 said slitting and take-up means for brushing opposite sides of the strips.

5. In a slitting and rewinding machine, means for holding a web supply, means for slitting the web into a plurality of strips, means for lubricating the moving web, means 85 for taking up each of the strips independently and in a plane at right angles to their plane of delivery from the slitting means, and means positioned between said slitting and take-up means for brushing opposite 90 sides of the strips.

6. In a slitting and rewinding machine, means for holding a web supply, means for slitting the web into a plurality of strips, means for lubricating the moving web, means 100 for taking up one of the strips independently and in a plane at right angles to its plane of delivery from the slitting means, means positioned between said slitting and take-up means for brushing opposite sides of the strips, means for taking up scrap material removed from the edges of the web, and means cooperating with the take-up means 105 for automatically compacting the scrap material wound thereon.

7. In a slitting and rewinding machine, means for holding a web supply, means for slitting the web into a plurality of strips, means for taking up each of the strips independently and in a plane at right angles 115 to their plane of delivery from the slitting means, means for brushing opposite sides of the strips before being taken up, means for taking up scrap material removed from the edges of the web, and means responsive to the building up of the scrap material for automatically compacting it on the take-up means.

8. In a slitting and rewinding machine, means for slitting a web into a plurality of strips, means associated therewith for taking up each of the strips independently and in a plane at right angles to their plane of delivery from the slitting means, means for deflecting the scrap material as it is formed, 120 125

- means for taking up scrap material, and means for automatically compacting the deflected scrap material on the take-up means.
9. In a slitting and rewinding machine, means for slitting a web into a plurality of strips, means for taking up each of the strips independently and in a plane at right angles to their plane of delivery from the slitting means, means for taking up scrap material, and means cooperating with the take-up means for automatically compacting the scrap material on the take-up means as it is formed.
10. In a slitting and rewinding machine, means for slitting a web into a plurality of strips, means for taking up one of the strips independently and in a plane at right angles to its plane of severance, and means cooperating with the take-up means for automatically compacting scrap material removed from the edges of the web.
11. In a slitting and rewinding machine, means for slitting a web into a plurality of strips, means for taking up each of the strips independently and in a plane at right angles to their plane of delivery from the slitting means, said means positioned above the plane of severance of the strips, means positioned below said slitting and take-up means and in vertical alignment with the last mentioned means for taking up scrap material removed from the edges of the web, and means cooperating with the take-up means for automatically compacting the scrap material thereon.
12. In a slitting and rewinding machine, means for holding a web supply, means for slitting the web into a plurality of strips, means for taking up one of the strips independently and in a plane at an angle to its plane of delivery from the slitting means, means for taking up the scrap material removed from an edge of the web, and means under spring tension for directing the scrap material to the take-up means and automatically compacting it thereon. 40
13. In a slitting and rewinding machine, means for holding a web supply, means for slitting the web into a plurality of strips, means for taking up one of the strips, means for taking up the scrap material removed from the edges of the web, and a channeled member cooperating with the take-up means to automatically compact the scrap material as it is wound on the take-up means. 45
14. In a slitting and rewinding machine, means for holding a web supply, means for slitting the web into a plurality of strips, means for taking up one of the strips independently and in a plane at an angle to its plane of delivery from the slitting means, means for taking up the scrap material removed from the edges of the web, and means having a curved portion cooperating with the take-up means to automatically compact the scrap material as it is wound thereon. 50
